UNITED STATES PATENT OFFICE.

THOMAS MEIKLE, OF CLEVELAND, OHIO.

HEATING-BOILER.

SPECIFICATION forming part of Letters Patent No. 475,459, dated May 24, 1892.

Application filed January 14, 1892. Serial No. 418,047. (No model.)

To all whom it may concern:

Be it known that I, THOMAS MEIKLE, of Cleveland, in the county of Cuyahoga and State of Ohio, have invented certain new and useful Improvements in Heating-Boilers; and I do hereby declare the following to be a full, clear, and exact description of the invention, such as will enable others skilled in the art to which it pertains to make and use the same.

10 My invention relates to improvements in heating-boilers, the object being to effect a more rapid circulation of the water or generation of steam, as the case may be, and to obtain greater economy in fuel than was possible with the boilers or heaters heretofore devised.

15 With this object in view my invention consists in certain features of construction and in combinations of parts hereinafter described, and pointed out in the claims.

20 In the accompanying drawings, illustrating a preferable construction of boiler embodying my invention, Figure 1 is a left-hand side elevation of the same with the inclosing brick casing in section. Figs. 2 and 3 are respectively a rear and a front elevation with the inclosing casing removed. Fig. 4 is a side elevation in section on line 4 4, Fig. 3. Fig. 5 is a horizontal section on line 5 5, Fig. 4.

25 30 A represents the inclosing casing, that in the present instance is of brick, casing A being provided in the usual manner with doors in front for firing and access to the interior, &c. The rear wall of the casing is provided with openings for the reception of rearwardly-extending flues B B', that are located the one above the other and connect with an upright flue C, flue B being provided with a damper, as at b.

35 40 D represents suitable frames or standards for supporting the superstructure, said frames or standards being provided with inwardly-projecting flanges d for supporting the grate E, that is of any suitable and well-known construction.

45 G represents a water box or reservoir that surrounds the fuel-chamber H and constitutes the base of the superstructure.

50 I represents a water-bridge that rests upon the rear portion of water-box G and extends to near the top of the inclosing casing A. Water-bridge I is preferably square or rect-

angular in shape, according to the dimensions of the boiler or heater, and is provided at its lower end and preferably at the central portion thereof with a flanged opening I', the flange being screw-threaded externally for screwing into a correspondingly and internally screw-threaded opening g' in the rearwardly and centrally enlarged portion g of rear member 6 of water box or reservoir G. The forward member 7 of reservoir G has connected therewith several heating and circulating tubes, that in the present instance are arranged in two rows, each row comprising three tubes at 65 either side of the central portion of member 7 of reservoir G, J and K representing the tubes in the respective rows. Tubes J and K extend to near the top of the boiler, where they connect with rearwardly-extending horizontal tubes J' K', respectively, that discharge into the water-bridge I, tubes K' being located below tubes J'.

Water-bridge I has connected therewith, preferably, vertical tiers of horizontal heating and circulating coils L, the coils extending lengthwise the boiler and preferably to near the forward end of the boiler, the pipe of the coils, excepting the coils located immediately above the grate or fuel-chamber, 80 being in open relation with water-bridge I at different elevations, as at l l'. The drawings exhibit nine tiers of coils and there being preferably as many coils in a tier as it is possible to have with the size of boiler or heater 85 employed. The coils located immediately above the grate or fuel-chamber are connected by an upright tube L² with rear member 6 of reservoir G, and are in open relation with water-bridge I, as at l'. Water-bridge I has 90 also connected and in open relation therewith rearwardly-extending short heating and circulating tubes M, that are longitudinally divided by a horizontal or approximately horizontal diaphragm M' to near the rear or closed 95 end of the tubes. The water-bridge at the upper end is provided with any desired number of distributing-pipes N for conducting off the heated water or steam, as the case may be.

95 N' represents the return-pipes that are connected, preferably, with one of the side members of reservoir G as near the bottom of the latter as is possible.

Damper b should only be opened in start-

ing the fire, and of course when open the products of combustion and a large share of the heat will pass through flue B; but when closed the products of combustion are obliged to 5 pass through flue B', and the heat is practically all retained within the boiler. Whether damper b is open or closed, however, in either case the products of combustion are first obliged to pass among the heating and 10 circulating tubes and coils forward of the water-bridge; but of course the escape of the products of combustion is much more rapid when damper b is open than when said damper is closed, and with the damper closed the 15 products of combustion are also compelled to pass among the heating and circulating tubes at the rear and down the rear surface of the water-bridge, and hence the heat of the products of combustion is utilized to the utmost 20 degree.

The economical results of my improved construction of boiler, it is believed, are quite apparent, as by the arrangement of parts shown an immense heating-surface is obtained and all the heat of the fuel substantially utilized.

My improved boiler, it will be observed, is also exceedingly simple in construction, and consequently can be quickly erected without 25 incurring much expense.

The circulation of the water, it is believed, will be readily understood; but arrows have been applied in the drawings to assist tracing of the circulation.

35 I would remark that I have reduced my invention to practice, and the boiler has proved about again as economical in fuel as the heating-boilers heretofore devised.

What I claim is—

40 1. In a heating-boiler, an inclosing casing, a water box or chamber arranged about the grate or fuel-chamber, a water-bridge in open relation with the rear portion of said water box or chamber, heating and circulating tubes connecting said water box or chamber and water-bridge, and one or more distributing-pipes connected with the water-bridge, substantially as set forth.

2. In a heating-boiler, an inclosing casing, a 45 water box or chamber surrounding the grate or fuel-chamber, a water-bridge located at the rear portion of and in open relation with said water box or chamber, heating and circulating tubes connecting said water box or chamber and water-bridge, heating and circulating coils located above the fuel-chamber within the inclosing casing and in open relation with said water-bridge, and one or more distributing-pipes connected with said water-bridge, substantially as set forth.

3. In a heating-boiler, an inclosing casing, a water box or chamber surrounding the grate or fuel-chamber, a water-bridge located at the rear portion of and in open relation with said 55 water box or chamber, heating and circulating tubes connecting said water box or chamber and water-bridge, heating and circulating

tubes located at the rear of and in open relation with the water-bridge and divided longitudinally to near the rear end thereof, and 70 one or more distributing-pipes connected with said water-bridge, substantially as set forth.

4. In a heating-boiler, an inclosing casing, a water box or chamber surrounding the grate or fuel-chamber, a water-bridge at the rear 75 portion and in open relation with said water box or chamber, upright heating and circulating tubes connected with the forward portion of the water box or chamber and connected with the water-bridge at the upper 80 portion of the latter, heating and circulating coils located above the fuel-chamber within the inclosing casing and in open relation with the water-bridge and heating and circulating tubes located at the rear of and in open relation with the water-bridge, and one or more 85 distributing-pipes connected with the water-bridge, substantially as set forth.

5. In a heating-boiler, an inclosing casing, a water box or chamber surrounding the grate 90 or fuel-chamber, a water-bridge at the rear portion and in open relation with said water box or chamber, heating and circulating tubes connected with the front and rear portions of said water box or chamber and in open relation with the water-bridge at different elevations, respectively, horizontal heating and circulating coils located forward of and in open relation with said water-bridge, and one or more distributing-pipes connected with said 95 water-bridge, substantially as set forth.

6. In a heating-boiler, an inclosing casing, a water box or chamber surrounding the grate or fuel-chamber, a water-bridge located at the rear portion and in open relation with said 100 water box or chamber, upright heating and circulating tubes connected with the forward portion of said water box or chamber and connected with the upper portion of the water-bridge, horizontal or approximately horizontal 105 heating and circulating coils located forward of and in open relation with said water-bridge, one or more of said coils connecting with the water box or chamber aforesaid, and one or more distributing-pipes connected with 110 said water-bridge, substantially as set forth.

7. In a heating-boiler, an inclosing casing, two flues in open relation with the interior of the boiler at the rear thereof and located in different horizontal planes relative to each 115 other, the upper flue being provided with a damper, a water box or chamber surrounding the grate or fuel-chamber, a water-bridge at the rear portion of and in open relation with said water box or chamber and heating and 120 circulating tubes connected with the forward portion of said water box or chamber and connected with the upper portion of the water-bridge, horizontal or approximately horizontal 125 heating and circulating coils located forward of and in open relation with the water-bridge, one or more of said coils being connected with the rear portion of the water box or chamber aforesaid, heating and circulating 130

tubes located at the rear of and in open relation with the water-bridge, and one or more distributing-pipes connected with said water-bridge, substantially as set forth.

5 8. In a heating-boiler, an inclosing casing, two flues in open relation with the interior of the boiler at the rear thereof and located the one above the other, the upper flue being provided with a damper, a water box or chamber 10 surrounding the grate or fuel-chamber, a water-bridge at the rear portion of and in open relation with said water box or chamber, heating and circulating tubes connected with the forward portion of said water box or chamber 15 and connected with the upper portion of the water-bridge, horizontal or approximately horizontal heating and circulating coils located forward of and in open relation with the water-bridge, one or more of said coils located immediately above the fuel-chamber 20 and being connected with the rear portion of the water box or chamber aforesaid, heating and circulating tubes located at the rear of and in open relation with the water-bridge, 25 one or more distributing-pipes connected with said water-bridge, and one or more return-pipes connecting with the water box or chamber aforesaid, substantially as set forth.

9. In a heating-boiler, an inclosing casing, a 30 water box or chamber surrounding the grate or fuel-chamber, a water-bridge at the rear portion of and in open relation with said water box or chamber, upright heating or circulating tubes connected with the forward 35 portion of said water box or chamber and connected with the upper portion of the water-bridge, vertical tiers of horizontal or approximately horizontal heating and circulating coils located forward of the water-bridge above 40 the grate or fuel-chamber, one or more of said coils connecting with the water-bridge and wa-

ter box or chamber, and the remainder of said coils being in open relation with said water-bridge at different elevations, heating and circulating tubes located at the rear of and in 45 open relation with said water-bridge and being divided longitudinally by horizontal or approximately horizontal diaphragms that extend to near the rear end of said tubes, one or more distributing-pipes connected with the 50 water-bridge, and one or more return-pipes connecting with the water box or chamber aforesaid, substantially as set forth.

10. In a heating-boiler, an inclosing casing, a water box or chamber surrounding the grate 55 or fuel-chamber, a water-bridge located at the rear portion of said water box or chamber, heating and circulating tubes connected with the forward portion of the water box or chamber and connected with the upper portion of 60 the water-bridge, heating and circulating coils located forward of and in open relation with the water-bridge, one or more of said coils being in open relation with the water box or chamber, the water box or chamber 65 having a rearwardly-projecting member, and the water-bridge having a flanged opening, the flange being externally screw-threaded for screwing into a correspondingly and internally screw-threaded hole in the rearwardly-projecting member aforesaid of the water box or chamber, and one or more distributing-pipes connected with the water-bridge, substantially 70 as set forth.

In testimony whereof I sign this specification, in the presence of two witnesses, this 14th day of December, 1891.

THOMAS MEIKLE.
